FOREIGN PATENT DOCUMENTS

U.S. Appl. No. 29/721,714, filed Jan. 22, 2020, Eldridge et al.

(Continued)

Primary Examiner — Mitchell I. Siegel(74) *Attorney, Agent, or Firm* — Wolf, Greenfield & Sacks, P.C.(57) **CLAIM**

The ornamental design for a ball marker and holder, as shown and described.

DESCRIPTION

FIG. 1 is a top, front, left side perspective view of a ball marker and holder according to our new design;

FIG. 2 is a top, front, right side perspective view thereof;

FIG. 3 is a rear elevation view thereof;

FIG. 4 is a bottom plan view thereof;

FIG. 5 is a front elevation view thereof;

FIG. 6 is a top plan view thereof;

FIG. 7 is a left side elevation view thereof; and,

FIG. 8 is a right side elevation view thereof.

The dot-dash broken lines represent boundaries of the claimed design and form no part of the claimed design. The dash-dash broken lines depict portions of the ball marker and holder that form no part of the claimed design.

1 Claim, 3 Drawing Sheets# US D939,654 S
